(57) **CLAIM**

The ornamental design for a portable tennis score board with remote control, as shown and described.

DESCRIPTION

FIG. 1 is a front elevational view of the portable tennis score board with remote control of the present invention; FIG. 2 is a rear elevational view of the portable tennis score board with remote control of FIG. 1; FIG. 3 is a left side elevational view of the portable tennis score board with remote control of FIG. 1; FIG. 4 is a right side elevational view of the portable tennis score board with remote control of FIG. 1; and, FIG. 5 is a top plan view of the portable tennis score board with remote control of FIG. 1, the bottom view being a mirror image thereof.

The broken lines showing of numbers in FIG. 1 are for illustrative purposes only and form no part of the claimed design.
